UNITED STATES PATENT OFFICE.

CHARLES MORRISON YOUNG, OF NELSON, BRITISH COLUMBIA, CANADA.

MUSICAL INSTRUMENT.

Application filed July 6, 1926. Serial No. 120,808.

This invention relates to improvements in musical instruments, and more particularly to glissophones and similar wind instruments, and the objects of the invention are to 5 provide an improved wind or reed instrument, in which an octave key is provided to take the place of two separate keys heretofore used in saxaphones.

Further objects are to provide an improved 10 instrument of this character of light weight and provided with an automatic octave key with few parts and which can be effectively and easily operated.

Further objects are the provision of an improved 15 wind instrument that can be manufactured at reasonable cost and placed on the market accordingly.

With the foregoing and other objects hereinafter more fully referred to in view, the essential 20 features of the invention are the combination with a single beam provided with a pair of pads and a direct operating lever and simple reversing means whereby one of the openings adapted to be closed by the pads is 25 opened while the opposite opening is closed. Another feature of the invention is the slide and octave key depending on each other and working together.

Referring now to the drawings, in which 30 like characters of reference indicate corresponding parts in each figure:

Figure 1 is an elevation of my improved wind instrument.

Figure 2 is a fragmentary view of the reverse 35 of Figure 1 showing the automatic key operating means,

Figure 3 is a section on line 3—3 of Figure 2,

Figure 4 is a side elevation of the instrument 40 shown in Figure 1, in which the sliding member has been moved endwise,

Figure 5 is a sectional detail view showing the slide member, and

Figure 6 is a section on the line 6—6 of 45 Figure 1.

Referring now more particularly to the drawings, in which a preferred example of my invention is disclosed, 10 designates the tube or the like of suitable material of substantially 50 conical formation with an open flanged end 11 and a restricted bent end 12, into which the mouth-piece 13 is fitted. In the bent end and adjacent the mouth-piece carrying end of the tubular body 10 are spaced 55 openings or orifices 14 and 15 for which nipple members 16 and 17 are provided. Rigidly

mounted at each end of a rocking beam 18 are pads 19 adapted to close the nipples 16 and 17 mounted on the beam 18 which is pivotally mounted substantially midway of its length at 20 on the operating beam 21, in turn pivotally mounted at 22 on the restricted end 12. A thumb piece 23 is formed integral with this beam 21 which, on being pressed, will tilt the beam on its pivot 22 compressing the spring member 24 rigidly connected thereto, and raising thereby the member 18 opening the nipple 16 on the aperture 15 in nipple 17 (see Figure 2).

Attached to and forming a part of the circumference of the tubular body 10 is a guideway or slide base 25 perforated by a plurality of spaced slots or the like 26 which connects the air within the body 10 with the outside atmosphere when not obstructed by the slide 27 designed to travel in the guideway 25, the guideway being formed with grooves on either side to slidably engage with the slide piece 27. The object of this slide is to open and close the openings or slots 26 in the guideway 25 through slot 27, thereby ascending or descending the musical scale according to the length of the air column within the tubular body 10 vibrated by the operation of blowing. The slide is also designed to carry 85 graduated scale markings 27^a, indicating the length of the air column as they stop at or pass the upper end of the slide base, and corresponding with the intervals of the musical scale as produced by the instrument.

On the body portion adjacent the rocking beam 18 is provided a reversing lever 28, pivotally mounted at 29 on the guide member 25 and designed, on the thumb piece 23 being pressed, to be engaged by the extension 30 on the slide 27, causing the orifice 14 to be closed by the pad 19 and the orifice 15 to be opened thereby doubling the range or compass of the instrument, and when disengaged by extension 30 to allow the tension of spring 31 to open the orifice 14 and close the orifice 15 while the lower register is effected by the release of the thumb plate 23 and the spring 24, drawing down the pivotal point 20, holding the pads 16 and 17 against the orifices 14 and 15, thereby closing them.

In my improved instrument an automatic octave key is provided with but three moving parts other than projection 30 of the slide and springs 24 and 31.

The main rocking beam or lever 18 is pivoted substantially midway to the operating

lever or beam 21 and supports at each end the closure members or pads 19 to cover the openings 14 and 15 in each of the nipples 16 and 17; an operating lever 21 pivoted to the instrument and adapted to pivotally support the main beam; and a reversing lever or rocker arm 28 pivoted to the instrument.

In operation, to play in lower register, move the point 32 of the slide 27 between the points 33 and 34 of the slide base 25; and to play in upper register move the point 32 of the slide between the points 33 and 34 of the slide base 25 and press thumb plate inwardly to tilt the beam or lever 21, compressing the spring 24 and raising the pivotal point 20 on the beam 18 opening the aperture 15 in the nipple 17, aperture in nipple 16.

As many changes could be made in the above construction and many apparently widely different embodiments of my invention, within the scope of the claims, constructed without departing from the spirit or scope thereof, it is intended that all matter contained in the accompanying specification and drawings shall be interpreted as illustrative and not in a limiting sense.

What I claim as my invention is:

1. In a musical instrument of the character described and in combination, a tubular body

portion provided with octave holes and 30 formed with a bent restricted end having spaced holes therein provided with nipples, a mouthpiece associated with said end, a slidably mounted closure member for selectively or collectively opening and closing the octave 35 holes, a pivotally mounted lever arm on the bent end, a rocking beam adapted to open and close the nipples and pivotally connected to the lever arm, and spring-pressed means on the body portion co-operating with the 40 rocking beam for opening one of the nipples in the bent end and closing the other nipples therein.

2. In a musical instrument of the character described, the combination with a tubular body portion having octave holes longitudinally thereof, a slidable closure member for said holes, a mouth-piece, spaced nipple members in the mouth-piece having openings therethrough, a lever arm associated with the 50 nipples and pivotally mounted substantially midway thereof, a rocking beam pivotally connected to the lever arm, a thumb piece formed integral with the beam whereby on the thumb piece being operated the beam is tilted. 55

In witness whereof I have hereunto set my hand.

CHARLES MORRISON YOUNG.
